Langendorf United Bakeries, Inc., San Francisco, Calif., a corporation of Delaware

Application November 10, 1943, Serial No. 111,644

Term of patent 14 years

(Cl. D59—2)

To all whom it may concern:

Be it known that I, Elsmore D. Lake, a citizen of the United States, residing at 5924 Monzal Avenue, Oakland, in the county of Alameda and State of California, have invented a new, original, and ornamental Design for a Bread Wrapping Paper, of which the following is a specification, reference being had to the accompanying drawing, forming part thereof.

The figure is a plan view of a bread wrapping paper showing my new design. One unit of the design is disclosed. Said unit is repeated vertically in regular succession as indicated by the broken lines.

I claim:

The ornamental design for a bread wrapping paper, as shown and described.
